PAGE 3

FIG-4-

I claim:

The ornamental design for a combined truck and lift, substantially as shown.
